UNITED STATES PATENT OFFICE.

SAMUEL HORELICK, OF PITTSBURGH, PENNSYLVANIA, ASSIGNOR TO PITTSBURGH TRANSFORMER COMPANY, A CORPORATION OF PENNSYLVANIA.

COOLING RADIATOR FOR TRANSFORMERS.

Application filed September 1, 1922. Serial No. 585,606.

To all whom it may concern:

Be it known that I, SAMUEL HORELICK, a citizen of the United States, residing at Pittsburgh, in the county of Allegheny and State of Pennsylvania, have invented certain new and useful Improvements in Cooling Radiators for Transformers, of which the following is a specification.

This invention relates to cooling means for transformers and particularly to auxiliary cooling apparatus adapted to be connected to a transformer tank to cool the oil in which the transformer is submerged. The object of the invention is to provide an auxiliary cooling means which will be strong and compact in construction and inexpensive in manufacture and having a large radiating surface so as to efficiently cool the circulating oil. Further objects of the invention, particularly in the building up of the cooler structure from stock material by bending and welding, will appear from the following description taken in connection with the accompanying drawings in which:

Fig. 1 is a plan view of a cooling device showing in dotted lines the internal construction.

Fig. 2 is an elevational end view of the same.

Figs. 3, 4 and 5 are horizontal sectional views illustrating the process of formation of the walls of the cooling apparatus.

Fig. 6 is a perspective view looking into the top of the cooling means at one end,

And Fig. 7 is a diagrammatic view showing a modification.

In the specific embodiment of the invention shown in the drawings the cooler C comprises top and bottom end plates H, H' joined to an intermediate body portion B. Each end plate H, H' comprises a metal plate 12 bent at 13 to form the plate into V-shape, the ends being cut in notched form so as to form triangular end spaces which are closed by triangular pieces 14 welded in place. Pipe connections 10 and 11 are welded to the top and bottom end plates respectively.

The body B of the cooler consists of steel sheets 15, 16 formed from stock metal by corrugating the sheets and assembling them so that the corrugations 15° of one sheet extend between the opposite corrugations 16° of the other sheet (see Fig. 3), thus leav-

ing narrow spaces 17 between the overlapping inner ends of the corrugations. This forms a passage of tortuous zig zag formation in transverse section so that a relatively small body of circulating oil has a large exposed surface.

To form a closed container of these corrugated sheets in assembled formation the outer bends 20 between the corrugations are flattened out as shown at 21 (see Figs. 4 and 6) to come together as indicated at 22. The ends of the corrugations 15°, 16° are preferably formed on inclined lines so as to form relatively inclined edges 23, 24 which may be readily turned over and tightly closed by welding as shown (Figs. 5 and 6). The end plates H, H' at their sides fit along the inclined surface 21 of the bends 20 between the corrugations, and the triangular end pieces 14 of the headers 75 similarly fit the inclined flange 26 of the sheet ends 16°, and the edges of the end plates are tightly welded in place so as to form a fluid tight structure.

The heated oil in the tank to which connections 10 and 11 are attached circulates through connection 10, downward through the spaces 17 in the body B wherein it is cooled and discharged out through the lower pipe connection 11 to the transformer tank. The inner surfaces of the sheets 15, 16 are thus in continuous contact with the oil while the outer surfaces of these sheets 15, 16 are in contact with the air so as to give a sufficient radiating and cooling action.

The cooler is readily built up to required size and formed from stock parts by simple cutting, bending and welding operations. It comprises vertically corrugated sheets 95 nested together in compact manner and welded together into a unitary structure of great strength. The circulating oil is spread out into a thin body in close contact with the cooling surfaces so that there are 100 no large bodies of oil remote from the cooling action.

Instead of connecting pipes 10 and 11 to the top and bottom end plates these connections may be brought in from the side as 105 indicated in Fig. 7.

In lieu of welding the parts may be brazed, or otherwise suitably fastened.

I claim:

1. A radiator having opposite corrugated 110

- sides and with the corrugations extending inward and with the outer bends flattened at the ends and an end plate welded to the flat portions of said sides.
5. A radiator having opposite corrugated sides and with the corrugations extending inward and with the outer bends flattened at the ends to form a support for an end plate, the ends of the corrugations being 10 bent over and welded so as to close their inner bends.
15. A radiator having opposite corrugated sides and with the corrugations extending inward and with the outer bends flattened at the ends to form a support for an end plate, the inner bends of the corrugations being closed by bending over and welding the ends of the corrugations on inclined 20 lines.
20. Cooling apparatus comprising a cooler having opposite corrugated sides and with the corrugations overlapping at the interior so as to form the oil passage into a succession of alternating relatively narrow inner and relatively wide outer spaces.
25. A radiator formed of two corrugated sheets of metal joined at its sides, the outer bends of the corrugations being closed at their ends so as to form inclined surfaces, 30 angular sheet metal ends for said radiator secured to said surfaces and extending in the direction thereof, to a central ridge.
35. A radiator having opposite corrugated sides, the corrugations overlapping at the interior, sides of the corrugations joining one another at their ends to close their inner bends and end members secured to said radiator sides and forming a space extending 40 across the closed ends of said corrugations and in communication with the space between said corrugated sides.
45. A radiator having a corrugated side, the inner bends of the corrugations being closed at their ends and the outer bends of the corrugations being closed to form a series of flat supporting surfaces, an end member having an inclined surface resting upon and secured to said flat surfaces, said end member forming a space extending 50 across the closed inner ends of said corrugations and communicating with spaces inside said radiator between said corrugations.
55. A radiator having a side formed of a single piece of sheet metal formed with a plurality of corrugations the inner bend of each corrugation being closed at its ends and the outer bend of each corrugation being closed to form surfaces which meet to 60 form a continuous supporting edge and an end member secured to said edge and form-
- ing a space inside the radiator extending across the closed inner bends of said corrugations.
9. A transformer radiator formed of a single corrugated body portion having its outer face freely exposed to permit dissipation of heat by rising air currents, said body portion comprising opposite corrugated sides, the inner bends of said corrugations being closed at their ends and the closed corrugations overlapping each other to form a thin space therebetween, and an end member joining the sides, extending over the closed ends of the corrugations and forming a space extending across said closed ends and in communication with the space between the inwardly projecting corrugations. 65
10. A radiator comprising opposite corrugated sides, the inner bends of said corrugations being inclined downwardly from the inside toward the outside at the bottom of the radiator, said corrugations being closed at their ends and the closed corrugations overlapping each other to form a thin space therebetween, and an end member joining the sides, covering the closed ends of the corrugations and forming a space extending across said closed 70 ends and in communication with the space between the inwardly projecting corrugations. 75
11. A radiator having a sheet metal corrugated side, the inner bends of the corrugations of said side being closed at their ends for the greater part of the depth of said corrugations and an end member for said radiator joining the side, covering the closed ends of the corrugations and forming a space extending across said closed 80 ends and in communication with the spaces inside said radiator between said corrugations. 85
12. A radiator having opposite corrugated sides, the inner bends of said corrugations being closed at their ends, said ends being inclined from the outside inwardly in a direction toward the central portion of the radiator and the closed corrugations overlapping one another to form a thin space therebetween, radiator ends forming spaces extending across the closed ends of said corrugations and in communication with the space between said inwardly projecting corrugations and means forming fluid inlet and outlet passages communicating with said end spaces, said radiator ends having walls which are inclined toward said 90 passages. 100
